BARBECUE GRILL

Charles Z. Papazian, 14680 Bredin Court,
Livonia, Mich. 48154

Filed Jan. 10, 1966, Ser. No. 542

Term of patent 3½ years

(Cl. D81—10)

The drawing is a front perspective view of the barbecue grill of the present design mounted for use, the fireplace shown in broken lines being included for illustrative purposes only.

I claim:

The ornamental design for a barbecue grill, as shown and described.
